CARL I. HAYES, OF PROVIDENCE, RHODE ISLAND

HEAT TREATING FURNACE

Application filed August 28, 1930. Serial No. 478,334.

My present invention relates to improvements in heat treating furnaces, and has particular reference to improvements for maintaining a constant gaseous atmosphere of desired constituency within the heat treating chamber.

A serious difficulty confronted during a heat treatment results from the changing atmospheric conditions within the heat treating chamber when opening the door thereof to insert material in or to remove material from the chamber. While one method of obviating this difficulty is to maintain an open mouth for the heat treating chamber, this method requires a much greater flow of gases to form an air excluding curtain than is necessary with a door closure; if sufficient gas flow is maintained to produce the desired treating atmosphere with the door closed, the outside air will penetrate through the protecting curtain when the door is opened and adversely affect the gaseous atmosphere in the heat treating chamber. One object of my invention is to reduce the amount of curtain gases necessary for adequate protection, and at the same time compensate for the door opening by regulating the gas flow so that an adequate curtain is provided with the door closed, and then providing an additional gas flow to reinforce the curtain gases and ensure adequate exclusion of the outside air when the door is open. This additional flow is preferably automatically controlled in accordance with the amount of door opening, so that the atmospheric conditions within the heat treating chamber remain constant regardless of the position of the door.

A further object of my invention is to shape the throat of the furnace so as to assist in the formation of a proper curtain, and to direct the gas flow to throw the upwardly flowing curtain gases forwardly towards the entrance to the heat treating chamber, thus further assisting in the formation of the curtain.

With these and other objects and advantageous features in view, the invention consists in a novel method and a novel arrangement of parts more fully disclosed in the detailed description following, in conjunction

with the accompanying drawings, and more particularly set forth in the appended claims.

In the drawings:

Fig. 1 is a front view of the improved heat treatment furnace, the doors being shown in closed position;

Fig. 2 is a central vertical section through the heat treating furnace on the line 2—2 of Figure 1;

Fig. 3 is a vertical section on the line 3—3 of Figure 2;

Fig. 4 is a horizontal section on the line 4—4 of Figure 2;

Fig. 5 is a view of a modified valve control for permitting independent manual control of the valves whenever desired.

It has been found desirable in constructing heat treatment furnaces, particularly furnaces of the electric type, to provide a protective gaseous curtain for the throat of the heat treating chamber, and to so regulate this gaseous curtain that it will maintain the desired atmospheric conditions within the heat treating chamber irrespective of the position of the furnace door. This regulation is preferably obtained by permitting a regulated flow of gases to form a curtain suitable for protection when the door is closed, and to provide an additional flow of gases to reinforce the curtain when the door is open; in addition, the throat is shaped to diverge towards the entrance opening and the gas flow is directed towards the entrance opening, in order to facilitate exclusion of the atmospheric air; and the following is a detailed description of a preferred construction which embodies the principles of my invention.

Referring to the drawings, the heat treatment furnace 10 is of standard construction, and is preferably mounted on vertical standards 11 in order to position the furnace opening at the proper height for easily inserting and removing articles to be treated. Within the heat treatment furnace is a heat treating chamber 12, having the usual throat 13 the entrance to which is normally closed by the vertically movable door 14 supported in the usual manner by cables 15 mounted on pulleys 16 and counterbalanced by a weight 100

or weights 17. The door 14 is preferably equipped with a peep-hole opening 18 which may have a closure shield, if desired, for permitting the operator to glance into the heat 5 treating chamber and observe the condition of the work therein. The chamber 12 may be heated in any desirable manner, but preferably is equipped with resistance bars 19 for receiving a heating current, thus heating the 10 work by radiation. A trough or channel member 20 is provided in the heating chamber and is mounted on suitable supports 21 and ledges 22, to receive the work to be heat treated.

15 Referring now to Figure 2, a combustion chamber 23 is positioned below the throat 13, and communicates with the throat through a vertical nozzle slot 24, which as shown in Figure 2 is parallel to the throat entrance 20 and is forwardly directed so as to throw the gases from the combustion chamber 23 against the upper wall of the throat 13. The combustion chamber 23 receives combustible gases and oxygen bearing gases through conduits 25 and 25' respectively, these conduits preferably being positioned outside the furnace and communicating with the combustion chamber 23 through any suitable nozzle arrangement or the like 26. The conduits 25 25 and 25' each have a by-pass line, designated respectively 27, 28, both the by-pass line and the main flow line for each conduit being provided with manually controlled valves, 29, 30, 31 and 32, two main cut-off valves also 35 being provided for each conduit. The conduits have further controls in that two additional valves 33, 34 are provided, preferably of the rotary type, adapted to be actuated by links 35, 36 which are connected at their 40 ends by a link 37, the linkage as a unit being actuated by reciprocating movement of a vertical rod 38 which is hingedly connected to an arm 39 mounted on the pulley shaft 40, whereby rotation of the pulleys by the usual 45 manually operated lever 40a to lift the door 14 also shifts the rod 38 and thus opens the valves 33 and 34 to automatically increase the supply of combustible gases and oxygen bearing gases in direct proportion to the door 50 opening.

The described arrangement operates as follows: The hand controlled valves 30, 32 are set to feed the desired proportions of air and gas to the combustion chamber, the door being in closed position. The valves 29, 31 are set to supply the door-controlled valves 32, 34 with the proper proportions of air and gas so as to maintain the desired atmospheric conditions in the furnace regardless of the 60 extent of opening of the door, it being desirable in the case of furnaces having relatively large door openings and therefore substantial exposure to the atmospheric oxygen, to set the valves 29 and 31 so as to feed an 65 excess of gas.

The rate of the gas flow in the conduits 25 and 25' may be visually observed by means of manometers 41, 42 mounted on the furnace and respectively connected to flow indicators 43, 44 positioned in the respective flow conduits. 70

Referring now to Figures 2 and 4, it will be noted that the throat 13 is preferably provided with walls diverging towards the entrance, thus assisting in throwing the curtain gases forwardly, this action being further assisted by the forward slant of the nozzle slot 24. 75

It may be preferable under unusual operating circumstances, to provide for hand control of the auxiliary valves 33 and 34. This is preferably accomplished by forming the end of the rod 38, as shown in Figure 5, with a vertical slot 45 therein and a transverse slot 46 centrally positioned with respect to the slot 45 and communicating therewith for receiving the pin 47 which connects the vertical link 37 with the upper valve link 35. The rod 38 is spring held by means of a coil spring 49 or the like so as to normally lock the pin 47 within the opening 46. If manual control of the valve 33 and 34 is desired, the rod 38 is swung forwardly, and the handle 48 of the link 37 is swung so as to bring the pin 47 out of the slot 46 and into the slot 45, whereupon the valves 33 and 34 may be shifted by movement of the handle 48 independently of the position of the door 14. 90

This control of the flow of gases into the combustion chamber 23 is suitable for maintaining the operating conditions in the heat treating chamber which are most desirable for the work under heat treatment. Thus, in the heat treatment of certain classes of jewelry, it is preferred to use hydrogen as the atmospheric medium; in this case, the adjustment of the valves 30 and 32 provides the minimum flow of hydrogen necessary to form a protective curtain when the closure member 14 is in down position; as the member 14 is lifted, the access of the outside air requires a greater flow of hydrogen, which is obtained by movement of the control valves 33 and 34 in exact accordance with the lifting of the door. 100

When a constant neutral gas atmosphere is desired in the heat treating chamber, the valves 29 and 32 are adjusted so as to obtain perfect combustion within the combustion chamber 23. The valves 33 and 34 are then adjusted in the same proportion, and serve to increase the amount of gases as the closure member lifts to still maintain the proper ratio between the two gases for complete combustion. 110

When heat treating high speed steels, a slight reducing atmosphere is found most desirable. In such case, the valves 30 and 32 are adjusted so as to obtain a slight excess of CO in the curtain gases, and the valves 125

29 and 31 are also adjusted so that as the closure member is raised, the additional flow of gases into the combustion chamber will always maintain the same suitable amount of 5 excess CO in the heat treatment chamber 12, the adjustment providing enough excess CO to prevent penetration of the atmospheric oxygen through the curtain.

While I have described a preferred construction of furnace, it is obvious that desired changes in furnace construction, in the number of openings, in the relative volumes and relationship of the various parts, and in the type of controls used, may be made to suit the 15 requirements of particular heat treatment installations, without departing from the spirit and scope of the invention as defined in the appended claims.

I claim:

20 1. In the art of heat treatment, the method of controlling the heat treatment of material in a heat treating chamber having an opening and a movable closure member for said opening, comprising supplying a gaseous 25 medium to said chamber to obtain a desired gaseous atmosphere therein, and increasing the supply of the gaseous medium to compensate for movement of said closure member to open position.

30 2. In the art of heat treatment, the method of controlling the heat treatment of material in a heat treating chamber having an opening and a movable closure member for said opening, comprising supplying a gaseous 35 medium to said chamber to obtain a desired gaseous atmosphere therein and to form an air-excluding curtain for said opening, and increasing the supply of the gaseous medium to compensate for movement of said closure 40 member to open position.

3. In a heat treatment furnace, a heat treating chamber having an opening, a movable closure member for said opening, means for supplying a gaseous medium of predetermined 45 constituency to said chamber, and means operating in accordance with movement of said closure member to maintain the same constituency of the gaseous medium in said chamber whether said closure member 50 is in open or shut position.

4. In a heat treatment furnace, a heat treating chamber having an opening, a movable closure member for said opening, means for projecting a gaseous medium across said 55 opening to form an air-excluding curtain therefor and to produce an atmosphere of said gaseous medium in said chamber, and means operating in accordance with movement of said closure member to maintain the 60 same constituency of the atmosphere in said chamber whether said closure member is in open or shut position.

5. In a heat treatment furnace, a heat treating chamber having an opening, a movable 65 closure member for said opening, means for

supplying a non-oxidizing gaseous medium to said chamber, and means for automatically changing the supply of gaseous medium in accordance with change in position of said closure member.

6. In a heat treatment furnace, a heat treating chamber having an opening, a movable closure member for said opening, means for projecting a non-oxidizing gaseous medium across said opening to form an air-excluding 70 curtain therefor and to produce an atmosphere of said gaseous medium in said chamber, and means for automatically changing the supply of gaseous medium in accordance with change in position of said closure mem- 75 ber.

7. In a heat treatment furnace, a heat treating chamber having an opening, a movable closure member for said opening, means for supplying combusted gases to said chamber 80 to form a work enveloping atmosphere, and means operating in accordance with movement of the closure member for maintaining the same atmospheric constituency in said chamber when said closure member is in open 85 or shut position.

8. In a heat treatment furnace, a heat treating chamber having an opening, a movable closure member for said opening, means for projecting combusted gases across said opening to form an air-excluding curtain therefor and to produce an atmosphere of said 90 gaseous medium in said chamber, and means operating in accordance with movement of the closure member for maintaining the same 95 atmospheric constituency in said chamber when said closure member is in open or shut position.

9. In a heat treatment furnace, a heat treating chamber having an opening, a movable closure member for said opening, means for supplying combusted gases to said chamber to form a work enveloping atmosphere, and means operating in accordance with movement of the closure member for increasing 100 the supply of gaseous medium upon opening of said closure member.

10. In a heat treatment furnace, a heat treating chamber having an opening, a movable closure member for said opening, means for projecting combusted gases across said opening to form an air-excluding curtain therefor and to produce an atmosphere of said gaseous medium in said chamber, and means operating in accordance with movement of the closure member for increasing the supply 110 of gaseous medium upon opening of said closure member.

11. In a heat treatment furnace, a heat treating chamber, a throat leading to said chamber, a closure member for the throat entrance, a nozzle slot in the bottom wall of said throat, a combustion chamber communicating with said nozzle slot, conduits for supplying combustible and combustion sup- 125 130

porting material to said combustion chamber, and means operating in accordance with movement of the closure member for increasing the supply of said material upon movement of said closure member to open position.

12. In a heat treatment furnace, a heat treating chamber, a throat leading to said chamber, a closure member for the throat entrance, the cross-sectional area of said throat increasing toward the throat entrance, a nozzle slot in the bottom wall of said throat, a combustion chamber communicating with said nozzle slot, and conduits for supplying combustible and combustion supporting fluid to said combustion chamber.

13. In a heat treatment furnace, a heat treating chamber, a throat leading to said chamber, a closure member for the throat entrance, the walls of said throat converging towards the throat entrance, a nozzle slot in the bottom wall of said throat, a combustion chamber communicating with said nozzle slot, conduits for supplying combustible and combustion supporting gas to said combustion chamber, and means operating in accordance with movement of the closure member for increasing the supply of said gas upon movement of said closure member to open position.

14. In a heat treatment furnace, a heat treating chamber, a throat leading to said chamber, a closure member for the throat entrance, a nozzle slot in the bottom wall of said throat positioned to direct gases issuing therefrom forwardly towards the throat entrance, a combustion chamber communicating with said nozzle slot, and conduits for supplying combustible and combustion supporting gas to said combustion chamber.

15. In a heat treatment furnace, a heat treating chamber, a throat leading to said chamber, a closure member for the throat entrance, the cross-sectional area of said throat increasing toward the throat entrance, a nozzle slot in the bottom wall of said throat positioned to direct gases issuing therefrom forwardly towards the throat entrance, a combustion chamber communicating with said nozzle slot, conduits for supplying combustible and combustion supporting gas to said combustion chamber, and means for increasing the supply of said gas upon movement of said closure member to open position.

16. In a heat treatment furnace, a heat treating chamber, a throat leading to said chamber, a closure member for the throat entrance, the walls of said throat converging towards the throat entrance, a nozzle slot in the bottom wall of said throat positioned to direct gases issuing therefrom forwardly towards the throat entrance, a combustion chamber communicating with said nozzle slot, means for supplying combustible and combustion supporting material to said com-

bustion chamber, and means for increasing the supply of said material upon movement of said closure member to open position.

17. In the art of heat treatment, the method of controlling the heat treatment of material in a heat treating chamber having an opening and a movable closure member for said opening, comprising supplying products of combustion to said chamber to obtain a gaseous atmosphere of predetermined constituency therein, and increasing said supply of products of combustion to compensate for movement of said closure member to open position, whereby an identical gaseous atmosphere is maintained in said chamber whether said closure member is in open or shut position.

18. In the art of heat treatment, the method of controlling the heat treatment of material in a heat treating chamber having an opening and a movable closure member for said opening, comprising supplying products of combustion to said chamber to obtain a gaseous atmosphere of predetermined constituency therein and to form an air-excluding curtain for said opening, and increasing said supply of products of combustion to compensate for movement of said closure member to open position, whereby an identical gaseous atmosphere is maintained in said chamber whether said closure member is in open or shut position.

19. In a heat treatment furnace, a heat treating chamber having an opening, a closure member for said opening, a combustion chamber, means for supplying combusted gases from said combustion chamber to said heat treating chamber, means for supplying a regulated amount of combustible gas and of air to said combustion chamber sufficient to exclude atmospheric air when said closure member is in closed position, and means for supplying a further regulated amount of combustible gas and of air to said combustion chamber to compensate for movement of said closure member to open position, whereby an identical gaseous atmosphere is maintained in said chamber whether said closure member is in open or closed position.

20. In a heat treatment furnace, a heat treating chamber having an opening, a movable closure member for said opening, a combustion chamber, means for projecting combusted gases from said combustion chamber across said opening to form an atmosphere excluding curtain, means for supplying a regulated amount of combustible gas and of air to said combustion chamber sufficient to form said atmosphere excluding curtain when said closure member is in closed position, and means for supplying a further regulated amount of combustible gas and air to said combustion chamber sufficient to maintain said atmosphere excluding curtain to com-

pensate for movement of said closure member to open position.

21. In a heat treatment furnace, a heat treating chamber having an opening, a movable closure member for said opening, a combustion chamber, means for projecting combusted gases from said combustion chamber across said opening to form an atmosphere excluding curtain, conduits for supplying combustible gas and air to said combustion chamber, valves in said conduits, by-pass conduits by-passing said valves, additional valves in said by-pass conduits and mechanism controlling said additional valves and operable to increase the supply of gas and air to said combustion chamber upon movement of said closure member to open position.

In testimony whereof I affix my signature.

CARL I. HAYES.
